UNITED STATES PATENT OFFICE

JOHNNYE LEE CASTON, OF CHICAGO, ILLINOIS, ASSIGNOR TO THE STERLING COMPANY,
OF CHICAGO, ILLINOIS, A CORPORATION OF WEST VIRGINIA

DESIGN FOR A DRESS

Application filed December 12, 1932. Serial No. 46,437. Term of patent 3½ years.

To all whom it may concern:

Be it known that I, JOHNNYE LEE CASTON, a citizen of the United States, residing at Chicago, in the county of Cook and State of Illinois, have invented a new, original, and ornamental Design for a Dress, of which the following is a specification, reference being had to the accompanying drawing, forming a part thereof.

Fig. 1 is a perspective front elevational view of a dress constituting my design.

Fig. 2 is a perspective rear elevational view of the dress shown in Fig. 1.

I claim:

The ornamental design for the dress as shown.

In witness whereof, I hereunto subscribe my name this 7th day of December, 1932, at Chicago, Illinois.

JOHNNYE LEE CASTON.
